MECHANISM HOUSING FOR RACING TOY

Hyman P. Boydman, Springfield, N.J., assignor to Topper
Corporation, a corporation of Delaware

Filed Feb. 27, 1969, Ser. No. 15,957

Term of patent 7 years

Int. Cl. D21—02

U.S. Cl. D34—5

FIG. 1

FIG. 3

F/G.2

FIG. 1 is a left side perspective view of a mechanism housing for a racing toy showing my new design;

FIG. 2 is a right side perspective view; and

FIG. 3 is a rear view.

I claim:

The ornamental design for a mechanism housing for racing toy, substantially as shown.
